(57) CLAIM

The ornamental design for an image forming apparatus, as shown and described.

DESCRIPTION

FIG. 1 is a front view of an image forming apparatus showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view as viewed from front direction thereof;

FIG. 8 is a perspective view as viewed from rear direction thereof;

FIG. 9 is a perspective view as viewed from bottom direction thereof;

FIG. 10 is a perspective view from front direction thereof showing the state in which a protective cover is attached;

FIG. 11 is a perspective view from rear direction thereof showing the state in which a protective cover is attached; and,

FIG. 12 is a perspective view from bottom direction thereof showing the state in which a protective cover is attached.

The broken line showing of a protective cover in FIGS. 10 to 12 is for illustrative purposes only and forms no part of the claimed design.
